UNITED STATES PATENT OFFICE

MAXIMILIAAN FREDERIK GUNNING, OF FLUSHING, NETHERLANDS, ASSIGNOR TO
NAAMLOOZE VENNOOTSCHAP: KONINKLIJKE MAATSCHAPPIJ DE SCHELDE SCHEEPS-
BOUW-EN WERKTUIGENFABRIEK, OF FLUSHING, NETHERLANDS, A CORPORATION
OF THE NETHERLANDS

SUBMARINE MINE LAYER

Application filed October 6, 1930, Serial No. 486,802, and in the Netherlands October 15, 1929.

The invention relates to a submarine-minelayer with a special mine-storage. In the known submarine-minelayers three different kinds of mine-storage are found. According to one of these the mines are arranged in tubes extending through the pressure body or through the auxiliary ballast tanks. With this construction the mines are continuously exposed to the influence of the sea water and cannot be kept in repair during the navigation.

Owing to this it has been tried to arrange the mines within the pressure-body, so that they are kept dry and may be kept in repair. In that case however, large compensation devices are required, and the mines must be ejected through a sluice.

Also a way between has been found by storing the mines on the pressure body below the upper structure. Then the mines are standing dry from time to time and with quiet weather they may be kept in repair when the submarine is proceeding at the surface of the water. However such an arrangement of the mines causes difficulties with regard to the stability, and already with a somewhat turbulent sea the mines are inaccessible and moreover they are placed in an exposed position.

The object of the invention is to remove all these drawbacks.

According to the invention the submarine is provided with one or more main ballast tanks of such a construction that the mines may be stored therein.

When the submarine is moving at the surface the mines are standing dry so that they may be kept in repair, may be provided with their detonator charge or adjustments of the depth regulator may be effected. Furthermore the mines are well protected, and neither sluices nor bulky compensation devices are required. Moreover the mines when arranged in a main ballast tank have no unfavourable influence on the stability.

Two embodiments of the invention will now be described by way of example with reference to the accompanying drawings.

Fig. 1 is a partial longitudinal section of one of the embodiments.

Fig. 2 is a cross section along the line II—II of Fig. 1.

Fig. 3 is a partial longitudinal section of another embodiment.

Fig. 4 is a cross section along the line IV—IV of Fig. 3.

In the embodiment of the Figures 1 and 2 the mines 2 are arranged in two main ballast tanks above each other.

In the embodiment of the Figures 3 and 4 however, they are arranged in a longer, continuous, but lower main ballast tank 3.

To this purpose these main ballast tanks are constructed so wide that the mines are accessible. Moreover the tanks are provided with a continuous longitudinal communication passage.

I claim:

Submarine-minelayer of the single hull type characterized in this that the main ballast tank(s) is (are) constructed and arranged as mine store room.

In testimony whereof I affix my signature.

MAXIMILIAAN FREDERIK GUNNING.
